UNITED STATES PATENT OFFICE.

MARSHALL W. GLEASON, OF BROOKLYN, NEW YORK.

DESIGN FOR A LAMP-SHADE.

SPECIFICATION forming part of Design No. 12,875, dated April 11, 1882.

Application filed January 25, 1882. Term of patent 7 years.

To all whom it may concern:

Be it known that I, MARSHALL W. GLEASON, of the city of Brooklyn, county of Kings, and State of New York, have originated and designed a new globe or shade to surround an illuminating-burner, and a pattern suitable for the shape, which may be etched, cut, or painted upon the same, of which the following is a full, clear, and exact description, reference being had to the accompanying drawing, making part of this specification, wherein—

A, E, I, and O represent the outline of the shade, and B, K, and N show the complete design for its ornamentation. Y Z represent a section of crown scalloped.

The contour of the globe may be described as follows: The whole is composed of a series of truncated cones whose lines converge and diverge, and the angles so arranged as to give the most pleasing effect. Crown A should, in a gas-globe, be eight inches in diameter at its upper extremity, run down and inward, and be about one and one-half inch long. At its lowest point it joins upper half of globe proper, 25 E, which with it forms an obtuse angle. Line E runs down and outward, and is about one and three-fourths inch long. At its lower end it joins lower half of globe I. This line should be about two and three-fourths inches long, 30 and, running down and inward, forms an obtuse angle with line E. At its lower end line I joins O, which runs out and downward, is three-fourths of an inch long, and forms flange or lip.

The foregoing description is about the proportion and angle of a so-called eight by four inch globe. To suit harps and drops of gas-fixtures of different design, and to be suitable for kerosene-lamps, (to admit various sizes and styles of chimneys, &c.,) it may be necessary to lengthen or shorten some of the lines of contour. For instance, when a globe shaped as described is made for a holder two and one-half inches diameter it will have a different angle and height from one made for five or six inch holder, though the general outline would be the same; and, again, if a globe at point formed by lines A and E were made larger or smaller in diameter, it would be made also higher or shallower thereby and the angles changed, 45 the design, however, remaining the same, which is broadly a series of truncated cones whose lines converge and diverge alternately, as shown and described.

When the globe is made of glass the design is etched or cut on in the usual manner, and 55 the contrast between the bright and ground or roughed work forms the design.

On a porcelain or opal glass globe or shade the design may be painted or transferred on in such suitable colors as may suggest themselves to the artist.

The design B for the crown A represents a number of circular ornaments not unlike a spread fan, which, when properly placed, should be about five-eighths of an inch apart. Between these ornaments I arrange a smaller one, representing an oak or similar leaf over a semi-circular base ornament. I prefer to arrange these in the manner stated, so that in case the globe is to be scalloped, as shown on crown 70 from Y to Z, the design will correspond with outline of scallop.

The design K on cone E represents a number of branches running parallel with each other, from each of which several twigs extend, 75 full of foliage. These branches are arranged at an angle between a top and a lower circle around cone, representing bands having similar rind as the branches mentioned.

The design N on inverted cone I represents 80 a number of solid semicircular bodies, smallest at base O, and gradually increasing in size as they near the top band. A suitable band encloses this part of design at its upper and lower extremity, as shown.

The whole design should go continuously around the globe or shade, though by arranging it in sections the effect would be substantially the same.

Globes used on illuminating-burners heretofore were ordinarily of the circular or "globe" pattern, in the full sense of the word. These were sometimes varied, contracted, and extended, such as "squats," "high," and "tulip" shape. A "cone" shape is also in use, 95 where, however, a single inverted cone constitutes the whole outline.

The so-called "crown" globe is similar to a squat globe, having the addition of an inverted cone top, perhaps one-fifth the height of whole 100 globe. These I do not claim.

Having fully described my invention, what I claim as new is—

1. A glass or porcelain shade or globe for an illuminating-burner, whose outline is composed of a series of truncated cones inverted 105

and converging at top A, then diverging at E, then converging at I, and then diverging at O, substantially as shown and described.

2. A glass or porcelain shade or globe for
5 an illuminating-burner, whose outline is composed of a series of truncated cones inverted and converging at top A, then diverging at E, then converging at I, and then diverging at O,

and ornamented by a design composed of the combination of the crown design B, cone design K, and design on inverted cone N, substantially as set forth and described.

MARSHALL W. GLEASON.
